UNITED STATES PATENT OFFICE.

BENJAMIN F. MCGUINNESS, OF GRAFTON, MASSACHUSETTS, ASSIGNOR TO CROMPTON & KNOWLES LOOM WORKS, OF WORCESTER, MASSACHUSETTS, A CORPORATION OF MASSACHUSETTS.

COMBINED THREAD CUTTER AND CLAMP.

Application filed August 1, 1924. Serial No. 729,633.

My invention relates to thread cutters and clamps for weft replenishing looms and it is the general object of the invention to provide improved means for holding an old end 5 of filling to prevent the same from being drawn into the cloth when the cutter and clamp are opened to receive a new end.

In weft replenishing mechanisms of the multi-color type it not infrequently happens that transfers will occur on successive detecting beats of the lay, the first transfer being for one shuttle and the next transfer for a second shuttle. At the time of transfer it is desirable to cut the filling of the 10 outgoing bobbin and clamp it so that it will not be drawn into the shed when the shuttle is picked but it is further desirable that the first end be held while the clamp is opening to receive the second end.

With this general object and other objects in view which will appear as the description proceeds, my invention resides in the combination and arrangement of parts hereinafter described and set forth in the 20 claims.

In the accompanying drawings, wherein I have shown one form of my invention,

Fig. 1 is a side elevation of a multi-color weft replenishing mechanism shown as 30 viewed from the central portion of the loom and having my invention applied thereto,

Fig. 2 is an enlarged section on line 2—2 of Fig. 1 showing the clamp in closed position,

Fig. 3 is a view similar to Fig. 2 but showing the clamps separated,

Fig. 4 is an enlarged horizontal section on line 4—4 of Fig. 1.

Fig. 5 is an enlarged side elevation of the cutter and clamp, and

Fig. 6 is a top plan view of the two part clamping element forming part of my invention.

Referring more particularly to Fig. 1 it will be seen that I have provided a weft replenishing mechanism having a frame 10 provided with a stud 11 on which is pivotally mounted transerrer arm 12. The upper portion of said arm 12 is provided with a roll 13 spaced from the arm and guided in bearing 14 on the arm 12 while the lower part of the arm is provided with a latch 15 which is lifted into operative position with respect to the bunter on the lay (not

shown) by connector 16, the upper end of 55 which is operatively connected to lever 17. Lever 17 is controlled as to position by means of top shaft 18 and the latter is provided with an arm 19 adjustably secured thereon and having pivotally attached thereto connector 20 which is yieldably attached to link 21. Said link 21 is connected at its lower end as at 22 to lever 23 which has a downwardly extending arm 24 supporting frame 25 of the combined cutter and clamp. 60 Lever 23 is pivoted on stud 26 carried by yoke 27, the latter being secured to stud 28 and positioned thereon by collar 29. The stud 28 passes through a bearing 30 which is bolted to the frame 10, and yoke 27 has a 65 forwardly extending arm 31 carrying pin 32 which passes through a collar 33 yieldingly mounted on rod 34. The lower end of rod 34 is pivotally connected as at 35 to the forward extension of the lower jaw 36 of a 70 clamp pivotally mounted on stud 37 carried by frame 25. Cutter blade 38 is fixed to the frame 25 and movable cutter 39 is connected as by a pin 40 to the lower jaw of the 75 clamp.

At the time of transfer the lever 19 is raised by the partial rotation of shaft 18 in the direction indicated by the arrow, the effect of which is to move lever 23 on stud 26 and move frame 25 and the parts supported thereby to the dotted line position shown in Fig. 1. Stud 32 remains stationary as frame 25 is moving rearwardly, the result of which is to lower the clamp 36 through the action of rod 34 and thus open the jaw of the clamp 80 and cutter. Roll 13 extends through a slot in depending arm 24 and as the transerrer descends the frame 25 is moved longitudinally of the lay. The matter thus far described is of common construction and for a 85 further description reference may be had to my prior Patent No. 1,261,417.

My invention relates more particularly to the construction of the clamp members as 90 shown more specifically in Figs. 2, 3 and 6. The lower element 36 of the clamp is composed of two parts 50 and 51 between which is located the tongue 52, the said parts and 95 tongue being held together by screw 53. The upper clamping element is also formed of two parts but in the latter instance the parts are held together yieldingly and provision is 100 made for their separation by the tongue 52.

Accordingly, I provide clamping sections 54 and 55, respectively, grooved as at 56 to receive helical spring 57 which lies in the groove 56 and normally holds the sections 54 and 55 together. The section 54 is provided with a lug 58 (see Fig. 6) and the section 55 is provided with a boss 59 having a spring pocket which is positioned to engage lug 58 when the two parts are assembled. The pocket receives spring 60 the tension of which is adjusted by screw 61 threaded into the frame 25 and the boss engages a web 62 formed on the frame 25 to limit downward movement of the clamping sections 54 and 55. Normally the cutter and clamp are closed as shown in full lines in Fig. 1, but at the time of transfer the cutter will move to the dotted line position shown in Fig. 1 with the clamps in the position shown in Fig. 3 and the trailing end of the weft W will pass between the upper and lower clamping elements. As the lay nears the front center frame 25 will be moved forwardly to raise the lower jaw, at which time the tongue 52 will pass between the sections 54 and 55, forcing the weft between said sections. The parts will remain closed until the next indication for transfer at which time the tongue will move from the position shown in Fig. 2 to that shown in Fig. 3 and the opposed teeth 63 of the sections will engage the yarn W to prevent withdrawal of the same by the tongue. The lower portions of the sections 54 and 55 are provided with teeth 64 and sections 50 and 51 are formed with teeth 65.

From the foregoing it will be seen that I have provided a thread clamp having two elements, one of which is composed of yieldable sections which are separated to receive the filling by a tongue extending from the other element and that the yielding sections serve to clamp the filling when the tongue is removed to prevent said filling from being released on the next operation of the clamp. Also, it will be seen that the tongue causes a greater length of thread to be taken up by the clamp so that said thread is acted upon by a relatively longer surface than is the case in my aforesaid patent.

Having thus described my invention it will be apparent that changes and modifications may be made therein by those skilled in the art without departing from the spirit and scope of the invention and I do not wish to be limited to the details herein disclosed, but what I claim is:

1. In a combined thread cutter and clamp for looms, means to cut the filling, a pair of clamping elements, one of said elements being formed of a plurality of yieldingly separable sections, and a tongue associated with the other clamping element to move the filling between the separable sections.

2. In a combined thread cutter and clamp

for looms, means to cut the filling, a pair of clamping elements movable relatively to each other, one of said elements being formed of a plurality of yieldingly separable sections movable toward and from each other in a direction transverse of the movement of said elements toward each other, and means to move the filling between the yieldingly separable sections, said sections being movable toward each other to hold the filling when said means is withdrawn. 75

3. In a combined thread cutter and clamp for looms, means to cut the filling, a carrier for said means, a pair of clamping elements pivotally mounted with respect to said carrier, one of said elements being formed of a pair of sections yieldingly held together, and a tongue projecting from the other element to move a filling end between the sections to separate the latter from each other, said sections being movable toward each other to clamp the filling when the tongue is withdrawn. 85

4. In a combined thread cutter and clamp for looms, means to cut the filling, a pair of clamping elements movable toward and from each other, one of said elements having a pair of sections, means to hold the sections together yieldingly, and a tongue movable with the other element and positioned to enter between and separate said sections to move the filling end between said sections, said sections being moved toward each other when the tongue is withdrawn to clamp the filling when the clamping elements are separated from each other. 95

5. In a combined thread cutter and clamp for looms, a pair of clamping elements, one of said elements being formed of a plurality of separable sections, means carried by the other element to separate the sections and move the filling therebetween, and means to cut the filling subsequent to the separation of the sections. 105

6. In a combined thread cutter and clamp for looms, means to cut the filling, a pair of clamping elements, one of said elements being formed of sections yieldingly held together and capable of movement apart in a direction substantially the same as the direction in which the thread to be cut extends, and a tongue carried by the other element to separate the sections and move the filling end between said sections, said sections being movable toward each other to clamp the filling when the tongue is withdrawn and said tongue being proportioned to separate the sections before the cutting means acts on the fillings. 110

7. In a combined thread cutter and clamp for looms, a carrier plate, cutting elements mounted on the carrier, a stud extending from the carrier, a pair of clamping elements pivotally mounted on the stud, said elements movable toward and from each 125

130

- other about the stud as a pivot, one of said elements being formed of a plurality of separable sections capable of slight movement toward and from each other in a direction substantially parallel to the stud, and means associated with the other element to engage the filling and cause the same to enter between the sections as the elements move toward each other.
8. In a combined thread cutter and clamp for looms, means to cut the filling, a pair of pivotally mounted clamping elements each having a grooved face to cooperate with a grooved face on the other elements, one of said elements being formed of a plurality of sections having adjacent surfaces extending transversely of the grooved faces of the ele-

ments, means carried by the other element to enter between and separate the sections, and resilient means to move the sections together as the tongue is withdrawn.

9. In a combined thread cutter and clamp for looms, means to cut the filling, a pair of clamping elements, one of said elements being formed of a plurality of yieldingly separable sections, yarn engaging teeth formed on adjacent surfaces of said sections, and means associated with the other clamping element to move the filling between the sections and into contact with the toothed surfaces thereof.

In testimony whereof I have hereunto affixed my signature.

BENJAMIN F. McGUINNESS.
